DESIGN FOR AN INK BOTTLE

Joshua Gordon Lippincott, Scarsdale, N. Y., assignor to L. E. Waterman Company, New York, N. Y., a corporation of New York

Application January 16, 1948, Serial No. 143,840

Term of patent 14 years

(Cl. D58—8)

To all whom it may concern:

Be it known that I, Joshua Gordon Lippincott, a citizen of the United States, whose post office address is 5 Reynals Crossing, Scarsdale, Westchester County, New York, have invented a new, original, and ornamental Design for Ink Bottle, of which the following is a specification, reference being had to the accompanying drawing, forming a part thereof.

I claim:

The ornamental design for an ink bottle, as shown.

JOSHUA GORDON LIPPINCOTT.
